ABSTRACT OF THE DISCLOSURE

A gas sterilization system is provided with means for dispensing a liquid sterilizing medium which is flash evaporated into a sterilizing gas and introduced into a sterilizing chamber. As the volume of the chamber being occupied by articles will vary considerably from load to load, the gas concentration within the chamber is monitored and when a predetermined concentration is obtained in the chamber, any surplus gas being generated is automatically exhausted.

This invention relates to a gas sterilizing system in which a predetermined quantity of liquid such as, for example, ethylene oxide is dispensed from a container and then flash evaporated into a gas for introduction into a sterilizing chamber containing articles to be sterilized.

Prior to sterilization, the articles are usually sealed in plastic bags which are permeable to the sterilizing gas but substantially impermeable to air-borne bacteria. A number of such bagged articles are loaded in the sterilizing chamber and the volume they occupy may vary radically from one load to the next load. For instance, there may be times when only a very small article is placed in the sterilizing chamber, and, at other times, several bulky items may be placed in the chamber to occupy most of its volume.

Such a sterilizing system is disclosed in copending application S.N. 592,127 filed Nov. 4, 1966, entitled, "Sterilizing Method and Apparatus." In the system disclosed in that application, the sterilizing gas is generated from a liquid dispensed from an aerosol supply cartridge. The cartridge has sufficient liquid to generate a quantity of gas to fill a substantially empty chamber with a predetermined concentration of sterilizing gas. When the chamber is filled to any appreciable extent with articles, there is an excess of liquid and gas available. To obtain the best results, however, the concentration of gas in the chamber should be controlled to a predetermined value irrespective of the chamber volume then being occupied.

It has been found that if the chamber is relatively full, then an excess of gas may be admitted and result in pressures in the chamber sufficiently large to break the hermetically sealed chamber, for example, by opening the access door to the chamber. In the above identified application, an operator manually controls the dispensing of liquid ethylene oxide, and, when the proper gas concentration is reached, the operator stops further dispensing of liquid. When the operator stops the dispensing, there is a residue in the aerosol canister of liquid which is potentially dangerous if the canister is incinerated.

Accordingly, a general object of the invention is to provide an improved and automatic gas sterilizing system to limit gas concentration in the chamber to a predetermined concentration.

A further object of the invention is to provide a predetermined concentration of gas in a sterilizing system irrespective of the amount of volume occupied by articles therein and to dissipate any residue of dispensing liquid or resulting gas.

2

Other objects and advantages of the invention will be apparent from the foregoing detailed description of the invention taken in connection with the accompanying drawings in which:

5 FIGURE 1 is a perspective view of a gas sterilization apparatus embodying the novel features of the present invention;

10 FIGURE 2 is a diagrammatic illustration of the operative connections between the operating elements with the sterilizing apparatus of FIGURE 1; and

15 FIGURE 3 is an exploded perspective view of the operating elements in a control unit of the sterilizing apparatus of FIGURE 1.

As shown in the drawings for purposes of illustration, 20 the invention is embodied in a sterilizing apparatus 11 which includes a housing 13 with a top cover 15 which opens to expose an interior chamber 17 (FIGURE 2) into which are placed the articles to be sterilized. Adjacent the chamber housing 13 is a control unit 19 for evacuating the chamber 17 and generating a sterilizing gas, such as ethylene oxide. The control unit is connected by a conduit line 23 to the interior chamber 17 in the housing.

Typically, the articles to be sterilized are packaged in 25 bags usually of polyethylene or other plastic material which can be penetrated by the ethylene oxide gas but which is impermeable to air-borne bacteria. To assist in the penetration of the bags by the gas and to assure a better microbicidal action, the chamber is subjected to partial vacuum prior to the introduction of the sterilizing gas into the chamber.

30 The system will be first described, very generally, as it relates to the system disclosed in copending application S.N. 592,127 filed Nov. 4, 1966 and entitled "Sterilizing Method and Apparatus," which is hereby incorporated by reference as if fully reproduced herein. Referring now to FIGURE 1 of the present disclosures, the operator places the articles in the enclosed chamber 13, closes the cover 15 for the chamber and fastens a 35 latch 27 to hermetically seal the chamber. An aerosol cartridge 25 is disposed within a cylindrical housing 29 which is fastened on the control unit 19 and a switch is operated to begin an operating cycle. During the first portion of the cycle, an exhaust means 31 in the form of a vacuum pump (FIGURE 2) is operated to exhaust the interior of the enclosed chamber. After a predetermined period of time, usually four minutes, the vacuum pump automatically shuts off and an electrically controlled dispensing valve 33 opens and permits the liquid ethylene oxide to flow past it and through a passageway into a heater 35. The liquid ethylene oxide then evaporates into a gaseous state. Because the liquid ethylene oxide is heated and subjected to the reduced pressure of the enclosed chamber 17 through the conduit 23 and the dispensing valve 33, it flash evaporates and quickly moves into the chamber 17. To offset cooling during the evaporation process, the electrical resistance heater 35 is provided with a tortuous passage to assist in a heat exchange from the heater to the evaporating liquid and gas. If the cooling is not offset, the rate of evaporation is reduced considerably. It is most desirable that the liquid ethylene oxide evaporates as it may polymerize and clog the conduit 23 and the dispensing valve 33.

35 In the system described in the copending application, the operator watched a pressure gauge 37 (FIGURE 1) on the cover 15 which indicated the build up of gas pressure within the housing chamber 17. When the pressure reached ambient pressure, the operator then unscrewed the aerosol container housing 29 which automatically operated the electrical switch resulting in closure of the dispensing valve 33. The spring loaded valve in the dispensing cartridge 25 also automatically closed and stopped

he dispensing of liquid ethylene oxide from the cartridge.

While the foregoing system operated satisfactorily and was much faster in operation than systems of the prior art, it sometimes occurred that the operator did not watch the pressure gauge 37 or would be slow in turning the cartridge housing 29 to cut off the dispensing of liquid. In the meantime, the ethylene oxide gas would continue to be generated and the concentration of gas within the housing would increase beyond that desired for best microbicidal action. Also the build up of excessive gas pressure in the housing exerted tremendous forces on the latch 27 and, in some cases, the housing lid could not be reained in the sealed position.

It will be appreciated that the housing chamber 13 has a fixed, volumetric capacity and the portion thereof occupied by the articles being sterilized often varies substantially from load to load. By necessity, the aerosol container 25 is sized to dispense sufficient liquid ethylene oxide to provide the proper gas concentration for a virtually empty chamber. When the chamber was loaded with an appreciable volume of articles, the operator had to diligently watch the pressure gauge 37 and shut off the system before excessive concentration and pressures were achieved in the chamber 17.

In accordance with the present invention, the proper concentration of gas is achieved within the chamber 17 irrespective of the volume occupied by articles being sterilized. Also, as a safety precaution the aerosol containers 15 are fully exhausted of liquid ethylene oxide automatically during each gas generation cycle. This is most desirable, as otherwise, operators may try to use a partially full cartridge for a subsequent sterilizing operation and unbeknown to them there will be insufficient liquid for sterilizing. In such a case, the articles would not, in fact, be sterilized although the operator may mistakenly think that they are sterilized because of having gone through a cycle with the apparatus. Also, incineration of cartridges having liquid ethylene oxide therein could result in an explosion.

To achieve the foregoing, the preferred embodiment of the invention contemplates monitoring the concentration of gas within the chamber and, when the concentration reaches a predetermined desired value, terminating the introduction of gas into the chamber followed by exhausting the remaining gas in the cartridge before terminating the cycle and removing the cartridge. As a result, the concentration of gas is controlled accurately and the dangers of undissipated liquid in the cartridge are avoided.

Referring now in detail to the apparatus similar to that disclosed in the above identified copending application and illustrated in FIGURE 3, the ethylene oxide cartridge 15 has a self-sealing valve and stem 43 (FIGURE 3) from which it will dispense a predetermined quantity of liquid which, in this instance, for a chamber having a capacity of three cubic feet of gas at ambient room temperature and pressure is approximately 90 grams of liquid ethylene oxide at a pressure of approximately 7 to 8 pounds per square inch at room temperature. The pressure is furnished by vapor pressure within the cartridge which is readily available as a standard item.

After loading the chamber 17 with the bagged articles and fastening the latch 27 to seal the cover 15, the operator places the cartridge 25 within the hollow cylindrical housing 29 with the stem 43 pointed downwardly.

Prior to beginning a sterilization cycle, the removable housing 29 is unthreaded from an upstanding sleeve on a base 45 secured on the outside of a top plate of the control unit 19. Then, the end of the cartridge opposite the stem 43 of the valve is inserted endwise into the bore of the bore of the receiver housing toward its upper radial end wall 47 and the housing is again threaded on the base. The valve stem 43 projects downwardly and its orifice is aligned with a bore or opening 49 extending axially through the receiver base 45. The lower end of the valve stem is positioned on the upper end wall of the

base and over the bore 49 in the latter. With the receiver housing 29 telescoped over the cartridge with its top wall 47 bearing against the now upstanding bottom end of the cartridge, an aperture 51 in the top wall of the housing is blocked by the adjacent cartridge end. The aperture 51 serves as an air inlet when not blocked by this end of the cartridge.

As the housing 29 is turned and threaded onto the receiver base 45, the lower end (FIGURE 3) of the housing moves into sealingly engagement with an annular outwardly projecting collar 54 (FIGURE 3) formed on the sleeve at the bottom of the external thread, and simultaneously the self-sealing stem of the valve of the aerosol cartridge is forced upwardly in the cartridge and opens to allow the liquid ethylene oxide to flow downwardly from the cartridge into the vertical, internal bore 49 in the receiver base and then to flow down through a depending threaded cylindrical sleeve 55 (FIGURE 3) screwed into a bore 57 in a top wall of the dispensing valve 36. Thus, it will be seen that the valve stem is spring biased to a closed position and the housing top wall 47 forces the cartridge to move down relative to the stem on the base and thereby the stem valve is opened.

Simultaneously with the screwing down of the housing 29 and the release of the liquid ethylene oxide, a microswitch 59 is operated to begin operation of a control circuit including a timer mechanism 61 (FIGURE 3). The timer mechanism is a commercially available timer having a motor (not shown) which is energized over leads 63.

An upstanding pin 65 on the microswitch 59 extends through an opening in an outwardly extending radial flange on the receiver base 45 to be depressed by the rim of the outer housing 29. The pin opens and closes contacts (not shown) which are connected to the timer mechanism 61 by leads 67 (FIGURE 3).

The timing motor begins a five-minute operation, after which, the timing motor automatically shuts off. During the first four minutes of timing motor operation, a vacuum pump motor 69 is operated to evacuate the chamber 17.

The pump motor 69 is fastened within the control unit and has its driving shaft connected to an impeller of a vacuum pump 71 which is fastened at one end of the motor. As the vacuum pump turns, it creates a suction in a conduit 73 extending from an inlet port 75 for the pump to a port 77 of an electrically operated, check valve 79. This check valve is normally closed and is operated to its open position only when the pump motor 69 is energized by the timing mechanism. The check valve 79 in its closed position prevents ambient air from leaking through the pump 71 and conduit 73 to the chamber 17 during the gas generation and sterilizing operations as will be explained.

The exhaust pump 71 exhausts through the check valve 79, which is now in an open position, and in fluid communication with a port of a multiported connector 81 which has a second port 83 in fluid communication with the conduit line 23 extending to the interior of the enclosed chamber 17. According to the preferred manner of operation, the vacuum pump 71 operates for approximately four minutes and reduces the pressure in the chamber to a predetermined vacuum, which is in the preferred embodiment of the invention, a vacuum of about 26 inches of mercury. The degree of evacuation of the enclosed chamber 17 may be varied, for instance, in the copending application the vacuum used was about 20 inches of mercury.

After the pump 71 has evacuated the chamber 17 for a predetermined period of time, the timing mechanism 61 de-energizes the pump motor 69 and closes the check valve 79; and simultaneously, the timing mechanism 61 energizes the solenoid operated dispensing valve 33 to release the sterilizing liquid for flash evaporation. The dispensing valve 33 is fixed to the bottom of the base 45 holding the cartridge 25 with its inlet opening 57 aligned and in fluid communication with the open stem

70 valve 33; and simultaneously, the timing mechanism 61 energizes the solenoid operated dispensing valve 33 to release the sterilizing liquid for flash evaporation. The dispensing valve 33 is fixed to the bottom of the base 45 holding the cartridge 25 with its inlet opening 57 aligned and in fluid communication with the open stem

valve of the cartridge 25. The dispensing valve 33 is normally in its closed position so that the liquid ethylene oxide is being blocked from moving toward the enclosed chamber 17. As the dispensing valve is operated to its open position, the liquid ethylene oxide is free to flow past its valve member (not shown) into a conduit pipe 85 leading to a tortuous passageway through the electrical heater 35 which is being operated by electrical resistance heaters under the control of the timing mechanism. The outlet of the heater passageway is connected by pipe 87 and pipe 89 to the multiported connector 81 leading to the line 23 extending to the evacuated chamber 17. The liquid ethylene oxide flowing from the dispensing cartridge 25 is subjected to the pressure differential emanating from the evacuated chamber 17 and this causes a flash evaporation of the liquid into a gas. The gas rapidly moves through the heater 35 into the enclosed chamber causing the pressure within the chamber to rise.

It will be appreciated that the liquid within the aerosol container 25 is being rapidly discharged and that the flash evaporation quickly generates the ethylene oxide gas so that the pressure within the chamber 17 rises quite rapidly. In the preferred cycle, the contents of the aerosol cartridge 25 will be dispensed through the valve 33 within one minute.

Referring now in detail to the preferred apparatus for practicing the improved method, the apparatus disclosed in the above identified copending application is modified by the addition of a vent control valve 39 which controls the flow of gas from the heater 35 and a monitoring unit 41 which monitors the concentration of gas within the chamber and controls the vent control valve in accordance with changes in the concentration. Conveniently, the monitoring unit determines the gas concentration by sensing its pressure within the chamber. To fill the chamber to the desired concentration, the movable element of the vent control valve is in a first position connecting the passages 87 and 89 between the heater and the chamber until the desired concentration is sensed by the monitoring unit. Then, the valve is actuated and its movable element is shifted to a second position to connect the heater line to an exhaust or bypass line 99 which is connected continuously to a common exhaust line 101 on the outlet side of the vacuum pump 31.

The monitoring device 41 herein is in the form of a pressure differential device with a pneumatically operated diaphragm 91 which has one side exposed to the ambient pressure and its other side exposed to the chamber pressure through a conduit pipe 93 connected to a port 94 for the multiported connector 81. Thus, the monitoring device 41 continually monitors the pressure of the gas within the chamber 17. In the present system, the proper gas concentration in the chamber 17 is obtained when the pressure in the chamber reaches ambient air pressure. It is within the purview of the invention that the pressure differential device be capable of adjustment to operate at pressures other than ambient. As the pressure in the chamber approaches ambient pressure, the diaphragm in the pressure sensing device moves to a position to operate an electrical switching device 97 which is open until the pressure differential is reduced to the point where the diaphragm which, in this instance, are electrical contacts, cause the contacts to close. These contacts control the electrical energizing circuit for a solenoid operating the vent control valve 39, which solenoid then becomes energized and causes a valve element to move to a position in which the valve connects the pipe 87 from the heater to a venting or bypass line 99. The bypassing line 99 is in turn connected to a common exhaust line 101 extending from the vacuum pump 71. The gas, if any, being generated from the surplus or residue liquid in the cartridge 25 or other connected apparatus is then diverted and exhausted from the system. The vent valve 39 remains in this position for the remainder of the five minute timer control cycle, which allows sufficient time

to assure that all of the ethylene oxide gas is evaporated from the aerosol cartridge 25, valve 33 and heater 35. At the end of the timing cycle, the timing mechanism 61 de-energizes the solenoid for the dispensing valve 33 which then moves to its closed position. The solenoid for the vent valve 39 is also de-energized at this time by the timing mechanism and returns to its normally open first position. Since both the dispensing valve 33 and the check valve 79 are closed, there will be no leakage from the enclosed chamber 17 through the control unit 19 during the sterilizing portion of the cycle.

For items which are extremely heat sensitive, it has been found that a three hour sterilizing cycle at room temperature is usually sufficient. Provision is made, however, to heat the chamber 17 and it has been found that the time required for sterilizing articles can be reduced considerably when heat and some moisture are employed with the gas. For example, when the chamber is maintained at approximately 140° F., a typical sterilization cycle can be reduced from a cycle of about three hours at room temperature to a cycle of about 48 minutes.

After the articles have been subjected to a gas for a sufficient time, the operator detaches the cartridge housing 29 and removes the cartridge 25. The operator then 25 resecures the housing 29 on the base 45 and thereby operates the switch 65. With operation of this switch 65, the timer mechanism 61 begins a new cycle and causes the motor 69 to turn the vacuum pump 71 to evacuate the ethylene oxide gas from the chamber 17 and exhaust the 30 same from the exhaust pipe 101 connected to the outlet side of the vacuum pump 71. After about four minutes, the pump motor 69 shuts down and the timing mechanism operates the valve 33 to its open position so that air may rush through the air inlet opening 51 of the now 35 empty cartridge housing 29 and through the valve 33 and the heater 35 and, now open, vent valve 39 into the exhaust chamber. At this time, the first wash cycle is completed. It is usually desirable to employ several washing 40 cycle. Therefore, the operator will again unscrew the receiver housing 29 and then screw the same now to reactivate the microswitch 65.

As an aid to understanding the invention, the operation of the improved apparatus will be reviewed.

Assuming the articles occupy approximately 1½ cubic feet of the three-foot chamber and that the cover 15 has been locked in place with the latch 27, an operator telescopes the housing 29 over an aerosol cartridge 25 and fastens the housing to the base 45 whereby the microswitch 65 is operated to begin the gas generating cycle. As the housing was fixed to the base, the spring bias valve from the aerosol cartridge was opened and liquid ethylene oxide was admitted to the inlet opening 57 of the dispensing control valve 33. However, no gas is generated so long as the valve 33 is closed.

55 The microswitch causes energization of the timing motor for the timing mechanism 61 which causes the operation of the vacuum pump motor 69 and the energization of the normally closed check valve 79 to its open position. The vacuum pump 71 operates for approximately four minutes at which time the evacuated chamber 17 has reached a vacuum corresponding to about 26 inches of mercury. At this time, the timing mechanism 61 de-energizes the motor 69 and the check valve solenoid, and the check valve then closes the line 73 from the vacuum pump 71 to the chamber 17 to prevent any leakage of air through the pump to the chamber.

70 During the operation of the vacuum pump 71, electrical heater elements in the heater 35 were operating to bring the heater up to temperature. When the vacuum pump 71 has shut down, the dispensing valve solenoid is energized to open the valve 33 and the ethylene oxide flows into the heater and flash evaporates in the presence of the subatmospheric pressure from the chamber 17. As the ethylene oxide evaporates, it flows into the chamber 75 17 and the pressure within the chamber rises as indicated

y the pressure gauge 37. The rise in pressure in the hamber is sensed by the monitoring unit 41, the in-
creasing pressure indicating an increase in gas concentra-
tion in the chamber. When approximately half of the
iquid from the dispensing cartridge 25 has vaporized and
as moved into the chamber 17, the pressure therein will
e approximately ambient pressure at which time the
onitoring unit 41 will close an electrical switching de-
ice 97 which operates the vent valve 39 to its second
osition in which the ethylene oxide gas is diverted
hrough it to a conduit 99 leading to the exhaust line
01. The vent valve 39 in this position closes the port
eading from the line 89 and chamber 17. The timing
echanism 61 continues until the end of its cycle and
hen automatically shuts off, at which time the dispensing
alve 33 returns to its closed position and the solenoid for
enting valve 39 is de-energized to return its valve to
s first or straight through position in which the chamber
7 is connected to the heater 35 and to the now closed
ispensing valve 33.

By this time, the cartridge 25 has been emptied of its
ntire liquid contents and the gas concentration within
e chamber 17 is being maintained at that concentration
est suited for microbicidal action. The articles are al-
lowed to remain in the enclosed chamber 17 for a period
sually ranging from about 45 minutes to about three
ours, depending on the type of sterilizing desired.

When the operator has decided that the articles have
een exposed for a sufficient time to the ethylene oxide
as, the operator will unscrew the cartridge housing 29
nd remove the cartridge 25 to expose the air inlet opening 51
at the top of the housing. Then, by screwing the
artridge housing 29 back on the base 45, the microswitch
5 is again operated to start a new cycle of the timing
echanism 63. The timing mechanism operates the motor
3 to evacuate the ethylene oxide gas from the chamber
hrough the now open check valve 79. The pump 71
ill now operate again for approximately four minutes
o remove the ethylene oxide gas from the bags and the
rticles. The timing mechanism will then cause the dis-
pensing valve 33 to open so that ambient air may flow
hrough the air inlet opening 51 and through the valve
3 to wash the same and into the chamber 17. When the
onitoring device 41 detects ambient pressure within the
hamber 17, it will operate the vent valve 39 to a pos-
on to let air flow from it for any remaining portion of
e timing cycle. Usually, the operation will perform two
uch washing cycles to assure removal of the ethylene
oxide from the various passageways and valves in the
ystem. If the ethylene oxide is allowed to remain in the 50
ystem, it will polymerize and eventually block passag-
eways and cause the valves to stick in a given position.
ince the pressure within the chamber 17 is at ambient
ressure at the end of a wash cycle, the cover 15 may be
pened and the articles removed.

From the foregoing it will be seen that the present in-
vention provides an effective method and apparatus for
utomatically controlling the gas concentration within the
erilizing chamber, limiting the pressure of the gas on
e chamber cover and emptying the dispensing cartridge
f liquid ethylene oxide.

While a preferred embodiment has been shown and
escribed, it will be understood that there is no intent
o limit the invention by such disclosure but, rather it
intended to cover all modifications and alternate con-
structions falling within the spirit and scope of the inven-
on as defined in the appended claims.

What is claimed is:

1. In a gas sterilizing apparatus, a chamber having a
predetermined capacity for receiving various volumes of
articles to be sterilized, a cover for closing an article ac-
cess opening in said chamber, an aerosol cartridge having
a valve and having a sterilizing liquid and a propellant gas

therein for dispensing said sterilizing liquid, means for
holding said valved aerosol cartridge in position to open
said valve to dispense said liquid, said aerosol cartridge
having a predetermined quantity of said liquid, means in-
cluding a pump for evacuating said chamber to a reduced
5 pressure below ambient pressure, means including a pas-
sageway from said aerosol cartridge to said chamber in
which said liquid will flash evaporate as it is exposed to
said reduced pressure, means to sense the pressure of said
gas within said chamber and to cause termination of flow
10 of sterilizing gas into said chamber, control means oper-
able by said sensing means sensing a predetermined gas
pressure, and means operable by said control means for
stopping the flow of gas to said chamber and for sweeping
15 the remaining excess sterilizing gas to exhaust, the sweep-
ing being done by the propellant gas, so that said chamber
has a predetermined concentration of sterilizing gas there-
in irrespective of the volume of the chamber that is oc-
cupied by goods to be sterilized and so that said aerosol
20 cartridge is exhausted during the sterilizing period.

2. The apparatus of claim 1 including a timer mecha-
nism operable for a predetermined cycle, said timer mecha-
nism operating said pump to cause operation of said
25 pump for a predetermined portion of said cycle, a dis-
pensing valve, said timer mechanism subsequently operat-
ing said dispensing valve for controlling a dispensing of
30 said sterilizing liquid for a time sufficient to discharge all
of said liquid sterilizing medium from said supply car-
tridge to said passageway and, said timer mechanism
operating said dispensing valve to return it to its closed
position after said surplus gas has had sufficient time to
exhaust through said valve.

3. The method of sterilizing articles with a gas such
as ethylene oxide comprising the steps of: placing the
35 articles into a sealed chamber having a predetermined
volume, evacuating air from the chamber to create a
partial vacuum within the chamber, connecting a supply
cartridge having a valve and containing ethylene oxide
40 with a propellant gas therein for vaporization and passage
as a gas into the chamber to provide a predetermined
gas concentration for a substantially empty chamber,
opening said valve to dispense said gas, introducing said
gas through conduits into this sealed chamber, monitor-
45 ing the concentration of gas within said chamber to
achieve a predetermined concentration of sterilizing gas
in said chamber irrespective of the volume of the cham-
ber that is occupied by goods to be sterilized, terminat-
ing the introduction of gas into said chamber when the
50 concentration of gas in the chamber reaches said pre-
dicted value, forcing said surplus gas being generated
from said cartridge to exhaust by said propellant gas
so that said supply cartridge is empty and may be im-
mediately removed prior to sterilization of said articles,
55 sterilizing said articles for a given period of time, and
conveying air through said conduits and chamber to wash
the residue of ethylene oxide therefrom.
